UNITED STATES PATENT OFFICE.

DAVIS MARINSKY, OF NEW YORK, N. Y.

COUPLING MEMBER FOR SEPARABLE FASTENERS.

Application filed March 15, 1926, Serial No. 94,711. Renewed June 23, 1928.

This invention relates to coupling members employed in connection with separable fasteners employing two parts having interlocking members adapted to be coupled and uncoupled together by said member which is 5 slideable longitudinally of the fasteners in this operation; and the object of the invention is to provide a coupling member of the class and for the purpose specified which is fashioned from a single body of predetermined material, preferably metal, by means of dies or molds; a further object being to provide a unitarily formed member of the class specified in which the diverging channels 10 are accurately formed, said channels having apertures opening outwardly through the sides of the coupling member to permit of the free passage of the shanks of the fastener therethrough; a further object being to provide 15 a coupling member of the class described with a finger piece guide and support formed integral with said member in the operation of casting the same and providing movement of the finger piece longitudinally of the coupling member in the operation thereof, means being provided to permit of the mounting of a finger piece which is independently formed, in connection with said coupling member, and for retaining the same against displacement 20 therefrom; a still further object being to provide a coupling member, the diverging channels of which are subdivided by an intermediate body portion which serves to join the upper and lower portions of said member or the opposite side faces thereof, and said body portion having forwardly directed fin-like extensions extending into that part of 25 said member where the diverging channels intersect; and with these and other objects in view, the invention consists in a coupling member of the class and for the purpose specified which is simple in construction and operation, efficient in use, and which is constructed as hereinafter described and claimed.

40 The invention is fully disclosed in the following specification, of which the accompanying drawing forms a part, in which the separate parts of my improvement are designated by suitable reference characters in each of the views, and in which:—

Fig. 1 is a diagrammatic view showing a part of a separable fastener with one of my improved coupling members mounted in connection therewith and illustrating the method 45 of its use.

Fig. 2 is a side view of the coupling member shown in Fig. 1 on an enlarged scale and with part of the construction broken away and in section.

Fig. 3 is a plan view of the coupling member shown in Fig. 2 with part of the construction broken away and in section; and,

Fig. 4 is an end view of the device shown in Figs. 2 and 3.

In Fig. 1 of the drawing, I have shown for the purpose of illustrating one use of my invention, the two parts 5 and 6 of a separable fastener, each part having link members 5^a and 6^a respectively, the link members 5^a being adapted to interlock with the link members 6^a to secure the separate parts 7 and 8 of a garment or the like together. At 9, in Fig. 1 of the drawing, I have shown one of my improved coupling members mounted upon the parts 5 and 6 of the fastener or the link members 5^a and 6^a thereof.

In the production of coupling members of the class under consideration, it is customary to construct these devices of two or more parts coupled together by riveting, welding or otherwise to form a coupling member having diverging channels and other structural features, but this method of procedure is rendered inexpensive and difficult in the handling necessary to perform the several operations, the cost of such devices, and the loss sustained in imperfect devices caused by inaccurate assemblage and the like, and it is the purpose of my invention to overcome these objectionable features and to reduce the manufacturing cost to the greatest possible extent in the production of perfect coupling members.

In carrying my invention into effect, I produce a unitary body by means of die casting or molding a suitable metal or any other hard and durable substance that will be suitable for the desired use. In the construction shown, the coupling member comprises two substantially similar side portions 10 and 11 joined at one end by a partition wall member or body 12 forming diverging channels 13 and 14 spaced apart by the member 12 at one end of the device. Said channels intersect at the contracted end of the device as clearly seen in Figs. 3 and 4 of the drawing. The end of the wall member 12 adjacent the contracted end of the channels 13 and 14 is beveled as seen at 12^a, Fig. 3 of the drawing, and extends in fin-like members 12^b onto the inner faces of

95

100

110

the side portions 10 and 11 of the device as seen in Fig. 2 of the drawing.

The channels 13 and 14 are substantially circular in form in cross section and open outwardly through the opposite sides of the coupling member through apertures 15 and 16 through which apertures, the shank portions of the devices 5 and 6 or the links 5^a—6^a thereof are adapted to pass.

10 The construction of the coupling member 5 or the formation or arrangement of the channels 13 and 14 therein which intersect at the contracted end of the device and diverge into separate discharges at the flared end of the device, is such as to permit of the free movement of the coupling member 9 over the links of the fasteners 5 and 6 in the operation of coupling and uncoupling the same, it being understood that the fin-like extensions 12^b 20 serve to enter the crevices formed between the links 5^a and 6^a of the fastener when coupled together, thus facilitating the free and easy operation of the coupling member in coupling and uncoupling the fasteners.

25 The enlarged or flared end of the coupling member 9 is provided centrally with a reduced extension 17, the top and bottom walls of which are beveled toward each other to form a contracted end 17^a, note Fig. 2 of the drawing. Extending centrally and longitudinally of the outer face of the coupling member 9 at one side portion thereof, the side portion 10 in the construction shown, is a rib 18 T-shaped in form in cross section and 30 forming a slideway for a finger piece 19, said rib forming at its opposite sides, channels 20 into which the yoke-shaped end 21 of the finger piece 19 is adapted to be placed to permit of the movement of the finger piece longitudinally of the coupling member from one end portion thereof to the other. The channels 20 are closed at the contracted end of the coupling member 9 as seen at 22, Fig. 2 of the drawing, and said rib extends around the 35 extension 17 and onto the opposite side portion 11 of the coupling member 9 to a slight extent as clearly seen at 23 in Fig. 2 of the drawing. It will be noted that the channels 20 normally open out through the rib 18 at the end portion 23 thereof as seen at 24 to permit the mounting of the finger piece 19 in connection with the rib 18. But, when said finger piece is mounted in position by passing the forked end 21 thereof over the projecting lip 25 of the rib 18, said rib is forced inwardly into the position shown in full lines in Fig. 2 of the drawing to prevent the accidental displacement of the finger piece 19.

60 It will be apparent that the rib construction 18 with the channels 20 at the opposite sides thereof, will permit the finger piece 19 to be moved from one end portion of the coupling member 9 to the other end portion thereof. As seen in Fig. 2 of the drawing, the finger piece 19 is brought into axial aline-

ment with the channels 13 and 14, thus facilitating the easy manipulation of the slider in the operation of coupling the links 5^a—6^a together, as seen in Fig. 1 of the drawing. When it is desired to uncouple the separable 70 fasteners 5 and 6, the finger piece 19 is moved into engagement with the closed end 22 of the channels 20 in the rib 18, and the coupling member 9 is moved in the opposite direction. The end 19^a of the finger piece is preferably 75 offset to provide a better grip for the fingers of the hand to facilitate the operation of the coupling member 9. However, it will be understood that I am not necessarily limited to any specific form of finger piece nor am I 80 necessarily limited to the specific arrangement of the structural features of the device herein shown and described nor the use herein illustrated, and various changes in and modifications of the construction herein set out may 85 be made within the scope of the appended claims without departing from the spirit of my invention or sacrificing its advantages.

Having fully described my invention, what I claim as new and desire to secure by Letters 90 Patent, is:—

1. A coupling member for separable fasteners comprising a unitary body consisting of substantially similar side portions united by a partition wall adjacent one end of the coupling member, channels formed between said side portions, said channels intersecting at one end of the coupling member and diverging at the other end thereof, said partition wall being tapered in the direction of the intersections of said channels, said channels opening through apertures at the opposite sides of the coupling member and formed between the side portions thereof, said channels being substantially circular in form in cross section, a rib integral with one side face of said coupling member and extending centrally and longitudinally thereof; and said rib having channels in the opposite faces thereof.

2. A coupling member for separable fasteners comprising a unitary body consisting of substantially similar side portions united by a partition wall adjacent one end of the coupling member, channels formed between said side portions, said channels intersecting at one end of the coupling member and diverging at the other end thereof, said partition wall being tapered in the direction of the intersections of said channels, said channels opening through apertures at the opposite sides of the coupling member and formed between the side portions thereof, said channels being substantially circular in form in cross section, a rib integral with said coupling member and extending centrally and longitudinally of one side portion thereof, said rib having channels in the opposite faces thereof, and the channels being closed at one end of said rib and normally opening outwardly at the other end of said rib.

extension at the other end of the body, and the side walls of the extension of said body and the rib member thereof being contracted to bring the end in horizontal alinement with the axis of the diverging channels in said body.

9. A die cast coupling member of the class described comprising a body contracted at one end and having a reduced extension at the other end, channels intersecting at the contracted end of said body and diverging with respect to the other end thereof, said channels being subdivided by a vertical partition wall member which is beveled in the direction of the contracted end of said body, said wall having fin-like projections extending onto the inner faces of the opposite side portions of said body, a rib member on the periphery of one side face of said body and extending from one end thereof to the other and onto the extension at the enlarged end of the body, the side walls of the extension of said body and the rib member thereof being contracted to bring the end in axial alinement with the axis of the diverging channels in said body, and said rib member having grooves in the opposite side faces thereof, said grooves being closed at one end of said body and open at the other end thereof.

10. A coupling member of the class described, comprising a molded body of unitary construction, diverging channels disposed at the opposite sides of said body and opening outwardly through the sides thereof, said channels intersecting at one end of the body and a grooved rib on the periphery of said body arranged centrally and longitudinally thereof, said rib being integral with one side face of said body and being T-shaped in cross sectional form to form a finger piece coupling

and guide, and said rib, extending beyond the opposite ends of said body.

11. A coupling member of the class described comprising a body having diverging channels disposed at the opposite sides and opening outwardly through the side edges thereof, a grooved finger piece guiding rib on the periphery of said body and arranged centrally and longitudinally thereof, said rib being T-shaped in cross sectional form to provide channels at the opposite sides thereof, said channels being closed at one end of the body and opened at the opposite end thereof, and a projecting tongue on said rib at the open end of said channel adapted to be moved into position to close the opening of said channel when the slide member is in use.

12. A coupling member of the class described comprising a body having diverging channels disposed at the opposite sides and opening outwardly through the side edges thereof, a grooved finger piece guiding rib on the periphery of said body and arranged centrally and longitudinally thereof, said rib being T-shaped in cross sectional form to provide channels at the opposite sides thereof, said channels being closed at one end of the body and opened at the opposite end thereof, a projecting tongue on said rib at the open end of said channel adapted to be moved into position to close the opening of said channel when the slide member is in use, and a finger piece slidably engaging said rib and having parts entering the channels thereof, said finger piece being retained against displacement from said member by said tongue.

In testimony that I claim the foregoing as my invention I have signed my name this 9th day of March, 1926.

DAVIS MARINSKY.
